UNITED STATES PATENT OFFICE.

CURTIS C. FELTNER, OF CERRO DE PASCO, PERU.

PITCHER FOR CANS OF CONDENSED MILK.

1,273,594.

Specification of Letters Patent. Patented July 23, 1918.

Application filed June 2, 1917. Serial No. 172,435.

To all whom it may concern:

Be it known that I, CURTIS C. FELTNER, a citizen of the United States, and a resident of Cerro de Pasco, Peru, South America, have invented a new and Improved Pitcher for Cans of Condensed Milk, of which the following is a full, clear, and exact description.

My invention relates to a pitcher which forms a container or receptacle for a can of condensed milk, so that the contents can be dispensed from the container in a sanitary and economical way without exposing the contents of the can to the direct action of the atmosphere when not delivering the contents from the can.

An object of the invention is to provide a simple, convenient, inexpensive and sanitary pitcher of the class described.

I attain the above and other objects of my invention by the structure conventionally disclosed in the accompanying drawings, wherein similar characters of reference indicate corresponding parts in all the views.

Figure 1 is a perspective view of the pitcher;

Fig. 2 is a vertical section therethrough showing a condensed milk container therein partly broken out to show the manner in which the can is apertured to permit the discharge of the contents;

Fig. 3 is an elevation of the pitcher, partly in section, in the position when discharging the contents of the can to the pitcher nozzle;

Fig. 4 is a horizontal section on line 4-4, Fig. 2, the can being removed; and

Fig. 5 is a section on line 5-5, Fig. 2.

Referring to the drawings, 6 is a pitcher of any suitable shape but of a size sufficiently large to accommodate easily therein a standard can for condensed milk through the top opening, for which a cover 7 is provided. The pitcher has a spout 8 having a lip 9 at the lower edge thereof forming a continuation of the body of the pitcher. This lip 9 forms a stop for a tongue 10 pivotally mounted within the spout, so that gravity normally tends to move the tongue against the lip when the pitcher is in the up-right position. When the pitcher is inclined or in position to discharge, as shown in Fig. 3,

gravity moves the tongue away from the lip toward the sectional cover 11 provided on the spout. This sectional cover hides the tongue within the spout and also keeps flies out therefrom.

The bottom 12 of the pitcher is at such a distance from the spout as to present the top of a can 13 above the lip 9 when resting on the bottom 12. The tongue 10 carries a pin 14 which enters the side discharge aperture 15 formed in the can in proximity to the top, the can being placed in the pitcher so that the aperture leads to the spout. A yielding member 16 is provided within the pitcher to engage the can and maintain the same on the bottom 12 of the pitcher. The bottom carries also a plurality of yielding members 17 which center the can within the pitcher so that the same is maintained in contact with the spout. The bottom 12 has a central opening 18 serving for forcing an empty can out of the pitcher.

The pin 14 on the tongue prevents the formation of a film at the discharge opening 15 which might interfere with the pouring out of the contents. It will also rupture any film that may be formed in the discharge opening after pouring out therethrough some of the contents.

While I have described the principle of operation, together with the device which I now consider to be the best embodiment thereof, I desire to have it understood that the device shown is merely illustrative and that such changes may be made as are within the scope of the appended claims:

I claim:

1. A pitcher having a side spout and a cover and adapted to receive a can through the top opening of the pitcher so that the upper part of the can is above the lower part of the spout, yielding means within the pitcher for engaging the can and maintaining the can in contact with the pitcher at the spout, a gravitationally-operable member within the spout adapted to engage the can in the spout when the pitcher is in an up-right position, and a sectional cover for the spout limiting the movement of the gravitationally-operable member from the can when the pitcher is in a position to discharge, the bottom of said pitcher having

a central aperture for facilitating the removal of a can from the pitcher through the top opening.

2. A pitcher adapted to receive a can so that the upper part thereof is above the lower part of the spout within the pitcher, a gravitationally-operable tongue within the spout, a lip at the lower part of the spout

for the tongue to limit its movement into the pitcher, an inwardly directed pin on ¹⁴ said tongue, and means in said pitcher for yieldingly engaging a can and retaining the same in the pitcher so that the can contacts with the pitcher at the spout.

CURTIS C. FELTNER.
